WATCH BALANCE SPRING TESTING DEVICE
AND CRYSTAL MICROPHONE THEREFOR

George T. Kuwada, New York, N. Y.

Application March 12, 1954, Serial No. 415,780

5 Claims. (Cl. 73—6)

This invention relates to a watch balance spring testing device and more particularly to a crystal microphone arrangement therefor.

This invention is an improvement upon the invention described in my copending application, Serial No. 386,192, filed October 15, 1953 for a Watch Balance Spring Testing Device.

It is an object of the present invention to provide a sensitive and satisfactory crystal microphone arrangement which will be effective, operable and efficient in use within the watch balance spring testing device disclosed in the above mentioned application.

It is another object of the invention to provide a crystal microphone arrangement for the watch balancing spring testing device which is in the form of a unit assembly easily secured to the underside of the sound box of the above testing device and wherein its pick up finger is projected through the supporting plate and will have direct contact with the watch as it is retained between the slide jaw assemblies and wherein the crystal will be rigidly held and supported through engagement with the finger post and the wire terminals in such a manner that it may not work loose or be easily destroyed.

Objects of the invention are to provide a crystal microphone arrangement for a watch balancing spring testing device which is of simple construction, inexpensive to manufacture, has a minimum number of parts, compact and consumes little space, durable and will have long life, easy to adjust and efficient in operation.

For other objects and a better understanding of the invention, reference may be had to the following detailed description taken in connection with the accompanying drawing, in which:

Figure 1 is a top plan view of the testing device showing the watch retaining slide jaws between which the watch is placed to effect the testing operation and with the finger of the microphone arrangement being extended into a position to rest against the watch when retained by the jaws;

Fig. 2 is a fragmentary vertical sectional view taken on line 2—2 of Fig. 1 and looking in full elevation upon the crystal microphone arrangement;

Fig. 3 is a transverse vertical sectional view taken on line 3—3 of Fig. 1, and looking in full elevation upon the rear end of the crystal microphone arrangement;

Fig. 4 is an enlarged bottom plan view of the testing device with the bottom plate removed and looking in plan upon the bottom of the crystal arrangement and upon the elongated sound box to which the crystal arrangement is attached;

Fig. 5 is a perspective view of the crystal arrangement removed from the testing device;

Fig. 6 is a perspective view of one of the terminal structures of the arrangement;

Fig. 7 is a fragmentary perspective view of another of the terminal structures of the arrangement.

Referring now to the figures, 15 represents a round hollow metal sound box or base having a bottom plate 16 fixed thereto by fastening screws 17 with a cushioning

2

gasket 18 disposed between the plate and the bottom edge of the base 15.

The base has a large thick flange 19 from which extends a lateral projection 20 having an opening 21 therein for receiving a supporting post 22 that can be rotated within the opening 21 so that its supporting arm 23 carrying center pin assembly 24 may be swung laterally. The vertical post 22 is secured in its adjusted position by a clamp screw 25. It is held against vertical displacement from the projection 20 by a washer 26 and a fastening screw 27 secured to the lower end of the post 22.

On the top of the flange 19 there is secured a circular plate 28 by means of fastening screws 29. This plate 28 has an elongated diametrically extending slot 30 in 15 which are adjusted opposing slide jaw assemblies 31 and 32 adapted to receive a watch 33 and retain the same for the purpose of a balance spring 34 being installed therein. Jaw fingers 35 and 36 will grip the end of the spring, and the end of the spring will be worked 20 through the jaw fingers to measure and determine the proper length of the balance spring that is being tested with the present testing device taken in connection with a time graph recording device, all in the manner as shown and described in the above mentioned application. The fingers 35 and 36 are carried on a slide 37 forming a 25 part of the center pin assembly 24.

The slide jaws 31 and 32 are respectively adjusted by diametrically opposed adjusting screws 38 and 39 respectively threaded in the respective slide jaw assemblies 31 and 32 in the sound box structure 46. The slide jaw assemblies 31 and 32 are guided on the top surface of the plate 28 by guideway members 40 and 41, respectively held upon the plate 28 by fastening screws 42 and 43. The inner ends of the adjusting screws 38 and 39 are joined together by a pin projection 44 on the screw 39 that enters an opening in the end of the screw 38. A stop washer 45 is carried on the pin projection 44 and is retained between the ends of the screws to prevent the slide jaw assemblies from engaging the respective opposite screws. These screws engage with depending portions of the slide jaws to adjust the slide jaws to clamping or unclamping positions.

Depending from the plate 28 under the slot 30 is a depending inner elongated sound box structure 46 held in place on the underside of the plate 28 by fastening screws 47. The adjusting screws 38 and 39 extend through the ends of this box 46 and are respectively held against outward displacement from the box and from the base 15 by washer and pin means 48.

Fastened to this inner elongated sound box 46 and upon the bottom side thereof is the crystal microphone arrangement indicated generally at 50, Fig. 5, and embodying the features of the present invention. This arrangement 50 has a U-shaped supporting bracket 51 that is secured to the underface of the box 46 by fastening screws 52 and 53. This bracket has depending legs 54 and 55 between which a T-shaped pivot arm 56 extends and into which there extends respectively from the pivot arm pivot pins 57 and 58.

On the end of the pivot arm 56 is a round enlargement 59 that carries a post 60 from which extends an upwardly and rearwardly bent finger 61. The supporting plate 28 has a hole 62 through which this finger extends and the guideway member 40 has a slot 63 in registry with the hole 62 and directed inwardly toward the underside of the watch. The upper end of the finger 61 will engage the underside of the watch to pick up any vibration therefrom resulting from the operation of the watch movement 33. The openings 62 and 63 are sufficiently large to permit a full swing amplitude of the finger 61 and so that the vibrations thereof will not be damped against the body of the device.

To retain the finger 61 against the watch is a bowed spring 64 having a bent end 65 extending and anchored to the underside of the supporting plate 28 and a bent end 66 extending into the top of the pivot support 56. The lower side of the spring 64 rests against the rear end of the pivot support 56 rearwardly of the pivot connection of the support 56 with the depending leg portions 54 and 55 of the bracket 51. This spring 64 will tend to keep the pivot support tilted in the manner so that the finger 61 will be held tightly against the underside of the watch works.

An upstanding stop pin 67 is mounted on the pivot arm support 56 to limit the upward movement of the finger 61 through the openings 62 and 63. This stop pin 67 will engage with the underface of the elongated sound box 46 and will limit the upward movement of the finger 61. The watch upon being placed over the finger will depress the pivot support against the action of the bowed spring 64 and cause the stop pin 67 to be dropped below the underface of the sound box 46.

The post 69 on the end of the pivot support arm 56 is recessed on one side as indicated at 68, Fig. 5, and within this recess there is supported one corner of a square shaped crystal 69 that extends rearwardly over the support 56 to a location just forwardly of the stop pin 67. This crystal may be of any variety such as to pick up vibrations delivered by the finger 61 to the post 69 in a manner to be excited and to alter the passage of electric current passing therethrough. One crystal is known as "Rochelle salt" but it will be apparent that other crystals may be used for this purpose.

A terminal strip 70 extends from the top surface of the crystal 69, over one side edge, and is connected to a depending projection 71 on the terminal bracket 72 secured to the underside of the enlargement 59 on the forward end of the pivot support 56, Fig. 7. A terminal strip 73 is connected to the underface of the crystal 69 and extends rearwardly for engagement with the terminal bracket 74 that has top and bottom mounting lips 76 and 77 that seat in one side of a U-shaped insulating block 78 that is carried by a portion of the pivot supporting arm extending between the bracket arms 54 and 55 in the manner as clearly shown in Figs. 2 and 5. A current supply wire 79 is connected to a forwardly extending sleeve projection 80 on the bracket 74. This wire is insulated and extends outwardly through the side of the box 15 as indicated at 81, and as shown in the prior application has a terminal plug by which it can be connected to a time graph recorder having a tape on which the vibrations of the watch are recorded.

Also, extending between the terminal brackets 72 and 74 in parallel circuit relationship with the crystal 69 is a small resistor 82. The forward end of the resistor is connected to a laterally extending projection 83 of the bracket 72 and the rear end of the resistor is connected to a laterally extending projection 84 of the terminal bracket 74. Electric current is supplied through the wire 79 and will enter the terminal bracket 74 and be delivered through the crystal and the resistor to terminal bracket 72. Terminal bracket 72 is mounted on the pivot support arm 56 and will conduct current to the pivot support arm 56 and to the spring 64 that may serve as a ground wire for grounding the current into the testing device.

It should now be apparent that there has been provided a simple and effective crystal microphone arrangement adapted for assembly within the balance spring testing device shown in the above mentioned patent application and which includes a bracket for the mounting of the same to the underside of the supporting plate of the device and a sensitive finger that extends upwardly through openings in the main supporting plate and in the guideway member for engagement with the underside of watch works while the watch works are being retained by the slide jaw assemblies 31 and 32. The vibrations are picked up from the watch and are delivered to the crystal 69 to excite the same and to alter the current

conditions within an electric current formed by a wire 79 delivering current to a rear terminal bracket 74 through a resistor 82 and the crystal 69, to a forward bracket 72 and from this forward bracket through the pivot support 56, the bowed spring 64 to the body of the device. If the proper length of balance spring has been selected, a proper reading will be had upon the time graph recorder. If not, the end of the balance spring 34 will be slid more or less through the finger clamps 35 10 and 36 of the center pin assembly 24.

While various changes may be made in the detail construction, it shall be understood that such changes shall be within the spirit and scope of the present invention as defined by the appended claims.

15. What is claimed is:

1. In combination, a balance spring testing device having a hollow base, a top supporting plate having an elongated sound box connected to the underside thereof below an elongated opening in said top plate and extending into the hollow base, slide jaw assemblies depending through the elongated opening and into the sound box, adjusting screws for adjusting the assemblies toward and away from one another, said assemblies being adapted to retain and support a watch works, guideway members on 20 the opposite sides of the slide assemblies serving to guide the movement of the slide jaw assemblies, means extending above the base and overlying the jaw assemblies for supporting one end of a balance spring of a watch while the watch is retained between the jaw assemblies, a crystal 25 microphone arrangement comprising a bracket secured to the underside of the elongated sound box and within the hollow base, a pivot arm support journaled upon the bracket, a spring connected between the pivot arm support and the top plate for urging upwardly one end of the 30 pivot arm support, finger means extending upwardly from said pivot arm support through openings in the top plate and the guide way member and adapted to be located in the space between the slide jaw assemblies and to engage with a watch retained there, a crystal member carried by 35 said pivot arm support, terminal brackets secured to said pivot arm support, one of said brackets being insulated therefrom, an electrical resistor and terminal elements extending from the crystal and the resistor to the corresponding terminal bracket and electrically connecting the 40 same in parallel circuit relationship with one another, a wire connected with one of said terminal brackets for directing electric current therethrough.

2. A crystal microphone arrangement adapted for use with a watch balance spring testing device comprising a bracket member adapted to be connected to the testing

50 device, a pivot arm support pivotally connected to the bracket member, an upstanding post at one end of the pivot support, a finger extending upwardly from the post and adapted to engage with the watch being tested, front and rear terminal brackets connected to the pivot support, 55 an insulating member provided on one of the brackets to insulate the same from the pivot support, a current supply wire connected to the insulated bracket, said upstanding post being recessed, a crystal block secured within the recess of the terminal post, terminal strips extending respectively from the upper and lower sides of the crystal block to the respective terminal brackets, a resistor having terminals connected respectively to the terminal brackets and spring means on the opposite end of the 60 pivot arm support adapted for engagement with the pivot arm to normally urge the same in one direction and the finger against the watch works, and said pivot support arm having transversely extending axle portions and being generally of T-shape, said bracket member being of inverted U-shape with leg portions depending outwardly of

65 the laterally extending portions of the pivot support arm and the laterally extending portions being journaled respectively in the respective leg portions, and a U-shaped insulating member extending upwardly and mounting 70 upon the one lateral extending portion of the pivot arm 75

support and serving to effect the insulating of the one terminal bracket, the one terminal bracket having lip engaging portion engaging with one edge of the insulating member, the other terminal bracket being grounded and electrically connected to the pivot support.

3. A crystal microphone arrangement adapted for use with a watch balance spring testing device comprising a bracket member adapted to be connected to the testing device, a pivot arm support pivotally connected to the bracket member, an upstanding post at one end of the pivot support, a finger extending upwardly from the post and adapted to engage with the watch being tested, front and rear terminal brackets connected to the pivot support, an insulating member provided on one of the brackets to insulate the same from the pivot support, a current supply wire connected to the insulated bracket, said upstanding post being recessed, a crystal block secured within the recess of the terminal post, terminal strips extending respectively from the upper and lower sides of the crystal block to the respective terminal brackets, a resistor having terminals connected respectively to the terminal brackets and spring means on the opposite end of the pivot arm support adapted for engagement with the pivot arm to normally urge the same in one direction and the finger against the watch works, and said pivot arm having an upstanding post, said finger means including said upstanding post and a flexible finger, said upstanding post having a recess in the side thereof, said crystal being generally flat and having one corner thereof extending into the recess and supported thereby upon the post to pick up vibrations imparted by the finger to the post and from the post.

4. A crystal microphone arrangement adapted for use with a watch balance spring testing device comprising a bracket member adapted to be connected to the testing device, a pivot arm support pivotally connected to the bracket member, an upstanding post at one end of the pivot support, a finger extending upwardly from the post and adapted to engage with the watch being tested, front and rear terminal brackets connected to the pivot support, an insulating member provided on one of the brackets to insulate the same from the pivot support, a current supply wire connected to the insulated bracket, said upstanding post being recessed, a crystal block secured within the recess of the terminal post, terminal strips extending respectively from the upper and lower sides of the crystal block to the respective terminal brackets, a resistor having terminals connected respectively to the terminal brackets and spring means on the opposite end of the pivot arm support adapted for engagement with the pivot

50

arm to normally urge the same in one direction and the finger against the watch works, and a stop pin for limiting the upward movement of the finger means secured to the upper face of the pivot support arm and having its upper end engageable with the underside of the elongated sound box and said spring connected between the top plate and the pivot arm support serving normally to urge the stop pin toward and into engagement with the elongated sound box.

5. A crystal microphone arrangement adapted for use with watch balance spring testing devices having a top plate, said microphone arrangement comprising a bracket member adapted to be connected to the testing device, a pivot arm support pivotally connected to the bracket member, and upstanding post at one end of the pivot support, a finger extending upwardly from the post and adapted to engage with the watch being tested, front and rear terminal brackets connected to the pivot support, and insulating member provided on one of the brackets to insulate the same upon the pivot support, a current supply wire connected to the insulated bracket, said upstanding post being recessed, a crystal block secured within the recess of the terminal post, terminal stops extending respectively from the upper and lower sides of the crystal block to the respective terminal brackets, a resistor having terminals connected respectively to the terminal brackets and spring means on the opposite end of the pivot arm to normally urge the same in one direction and the finger against the watch works, said spring being bowed in shape and having an upstanding end projection at one end thereof for engagement with the top plate of the testing device and a depending projection at the opposite end thereof projecting into said terminal support, said spring bearing against the rear end of the pivot support and having its lower terminal end connected above the pivot connection of the pivot support arm with said bracket, and stop pin means secured to the pivot arm support forwardly of the mounting bracket and engageable with the underside of the testing device upon which the bracket would be mounted.
